ATTORNEY.

UNITED STATES PATENT OFFICE.

HARRY E. POWELL, OF ANDERSON, INDIANA.

BED-SPRING.

1,345,235.

Specification of Letters Patent. Patented June 29, 1920.

Application filed July 19, 1919. Serial No. 311,920.

To all whom it may concern:

Be it known that I, HARRY E. POWELL, a citizen of the United States, residing at Anderson, in the county of Madison and State 5 of Indiana, have invented new and useful Improvements in Bed-Springs, of which the following is a specification.

This invention has reference to improvements in bed bottoms and is especially directed to the frames for bed springs.

The object of the invention is to produce a bed spring frame of a novel construction wherein the tension of the springs may be readily regulated and also wherein the parts 15 constituting the frame may be separated for convenience in handling, storage, etc., means being provided whereby the said parts may be easily and quickly assembled.

A further object of the invention is to produce a frame for bed springs that shall be light, strong, durable but which at the same time may be manufactured with comparative cheapness.

Other objects and advantages will present 25 themselves as the nature of the invention is better understood, reference being had to the accompanying drawings, in which:

Figure 1 is an enlarged side elevation of one of the corners of a frame illustrating 30 the manner of adjusting the bracket on the side member or rail of the frame.

Fig. 2 is a sectional view approximately on the line 2—2 of Fig. 1.

Fig. 3 is a perspective view of the compressible sleeve and the elements associated therewith.

Fig. 4 is a view of the rotatable element having the cam wheel thereon.

The side rails of my improved frame are 40 preferably in the nature of tubes, in any event being round in cross section. While only one end member is illustrated by the drawings, it is, of course, to be understood that two of such members are employed in 45 the construction of the frame. The side member is indicated by the numeral 10'. On the ends of the side rails 10' are the barrel portions 13' of the corner brackets 14'. The brackets are in the nature of castings and 50 support the end rail to which the spring bottom is secured.

On the rail 10', inward of the bracket 14' is a sleeve 28 which is in the nature of a split member having at its slotted side outwardly extending lugs 29—29 which, of course, are spaced from each other but are

arranged in parallelism so that one is disposed directly over the other. The lower lug has a threaded opening 30 and the upper lug has a non-threaded and preferably larger opening 31 that registers with the opening 30. Through these openings pass the threaded shank 32 of a bolt member, the head of the said bolt member, as indicated by the numeral 33, rests upon the outer face 65 of the lug 29 provided with the opening 31 when the threaded shank thereof engages with the threads in the opening 30 and compresses the lugs toward each other to force the split sleeve 29 into frictional engagement with the side rail 10'. The sleeve, upon what I will term the outer face thereof has formed thereon a centrally disposed plate 34 that projects a suitable distance below the sleeve and has, adjacent its lower 70 end a transverse opening 35. On the plate 34, approximately centrally of the bore of the sleeve 28 is a stub shaft 36 having a threaded socket 37 entering centrally from its outer end.

The numeral 38 designates a revoluble member which is preferably flat and provided with a round periphery. This member is centrally formed with an opening 39 that is received on the stub shaft 37, and the 85 said member, adjacent to its periphery is provided with spaced round openings 40 any one of which being designed to register with the opening 35 in the plate 34, and passing through these registering openings is a pin 90 40 that has its head portion enlarged and knurled, the said head being indicated by the numeral 41. Eccentrically formed on one of the faces of the member 38 is a wheel 95 42. It will be apparent that when the member 38 is turned on the stub shaft 36 the cam wheel 42 will be brought into engagement with the inner end of the barrel 13' of the bracket 14', and as the bed springs are attached to the bracket, it will be apparent 100 that by properly adjusting the wheel 40 the cam wheel 42 thereon will retain the bed springs at proper tension.

On the outer face of the stub shaft is a washer 43 having a central opening, and 105 passing through the said opening and engaging with the threads in the bore 37 is a bolt member 44.

Having thus described the invention, what is claimed as new, is:

1. In combination with the side rail of a bed and a longitudinally movable spring

carrying bracket on the end thereof; of means carried by the said rail contacting with the bracket for limiting and adjusting the inward movement of the bracket on the rail, said means comprising a pivoted rotary member secured on the rail and an eccentrically mounted disk thereon, and means also carried by the rail and engaging with said disk for holding the same in contact with the bracket.

2. In combination with the side rail of a bed and a longitudinally movable spring carrying bracket on the end of said rail; of means for limiting and adjusting the inward movement of the bracket on said rail, comprising a sleeve secured to the rail, an

apertured plate thereon, a stub shaft carried thereby, a revoluble disk-shaped member journaled on the stub shaft, said member having spaced apertures adjacent to the periphery thereof, an eccentrically mounted wheel on one of the faces of the said member designed to contact with the inner end of the bracket, and an element adapted to pass through the apertured plate of the sleeve and one of the apertures in the revoluble disk for regulating the contacting engagement of the eccentrically arranged wheel with the inner end of the bracket.

In testimony whereof I affix my signature. 30

HARRY E. POWELL.
